(57) **CLAIM**

The ornamental design for a viscous liquid dispenser, as shown and described.

DESCRIPTION

FIG. 1 is a perspective view of the embodiment of the new dispenser design according to the invention.

FIG. 2 is a front view of the embodiment depicted in FIG. 1.

FIG. 3 is a right side view of the embodiment depicted in FIG. 1.

FIG. 4 is a left side view of the embodiment depicted in FIG. 1.

FIG. 5 is a top view of the embodiment depicted in FIG. 1.

FIG. 6 is a bottom view of the embodiment depicted in FIG. 1; and,

FIG. 7 is a back view of the embodiment depicted in FIG. 1.

The broken-line disclosure in the views is for illustrative

purposes only and forms no part of the claimed design.
